(57) **CLAIM**

The ornamental design of laser engraving and cutting machine as shown and described.

DESCRIPTION

FIG. 1 is a first front perspective view of a laser engraving and cutting machine according to my new design;

FIG. 2 is a bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines immediately adjacent to the shaded areas depict the bounds of the claimed design, while all other broken lines are directed to environment. The broken lines in the figures form no part of the claimed design.

1 Claim, 8 Drawing Sheets
